UNITED STATES PATENT OFFICE

CHARLES V. PROCTOR, OF BIRON, WISCONSIN

PROCESS AND APPARATUS FOR REGULATING PAPER STOCK AND THE LIKE

Application filed January 11, 1929. Serial No. 331,742

The present invention relates to a process and an apparatus for measuring the principal ingredients used in making paper and also for changing the proportions of such ingredients before they are mixed.

The invention comprehends the building of reservoirs into which ingredients are fed under pressure, which reservoirs are provided with overflows allowing the excess ingredients to return to the main supply container; a measuring chest attached to these reservoirs which are built on inclines with moving gates so arranged as to allow the ingredients, when the outer gate is closed and the inner gate open, to flow into and fill the measuring chest adjustable as to capacity and then to flow out of the measuring chest when the inner gate is closed and the outer gate is open, and to flow into a box or chest where the ingredients are mixed; the gates to be opened and closed automatically and timed by an arrangement of gears and pinions, which pinions are connected to crank shafts and the crank shafts are connected to a gate by a connecting rod.

The invention further comprehends an adjustable plunger in the measuring chest proper which is adjustable to increase or decrease the capacity of the chest as is desired by the operator within certain limits.

The invention further comprehends the erection of a gauge on the adjustable plunger to indicate the capacity of the measuring chest proper at different positions of the plunger.

The invention further comprehends a suitable air vent in such measuring chest proper to allow the free passage of air to and from such measuring chest so as to avoid the trapping compression of air as the chest fills, and also to avoid vacuum as the chest empties.

The invention still further comprehends special gears and pinions so arranged as to time the action of the gates and with spe-

cially arranged cogs to give such gears and pinions additional strength at the beginning of their operation.

An important object of the invention resides in the provision of an apparatus of this nature which is simple in its construction, compact in its arrangement of parts, strong and durable, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of the apparatus embodying the features of this invention,

Figure 2 is a front elevation thereof, and

Figure 3 is a vertical section therethrough.

Referring to the drawing in detail it will be seen that the letter C denotes generally a chest on suitable supports 5 rising from a suitable base 6. This chest C is formed with an inclined bottom 7, partition walls 8 to form a plurality of compartments A and baffle walls 9 rise at the rear or upper end of each compartment A separating the compartments A from overflow 10.

Except for size the compartments A are substantially the same and a detailed description of one will suffice for all except for certain details as will be mentioned. A bearing 11 is provided in the top of each compartment to slidably receive a shank 12 with a valve plate 14 fixed on the lower end thereof. In the central compartment which, in the present example, is wider than the other compartment there are two of the shanks 12.

Grooves 15 are provided in the bottom 7 between the lower ends of the valves or gates 14. The front walls of the compartments are

formed with openings 16 leading into main spout 17 which is removed in Figure 2 and gate valves 18 are slidable in suitable guide means 19 to close and open the openings 16.

5 Shanks 20 are slidable through bearings 21 in the upper wall of the chest and have the gate valves 18 secured to their lower ends. Vents 22 rise from the compartment A between the gates 14 and 18 which will be 10 specifically referred to hereinafter as the lower portions of the compartments. Plungers 23 are slidable through openings 24 and inclined means 25 is provided to prevent the turning of these plungers.

15 Threaded rods 26 rise from the plungers and have threaded thereon hubs 27 of worm gears 28 journaled in brackets 29 and operable by worm shafts 30 journaled in brackets 31 and having hand wheels 32. Gauges 34 20 rise from the brackets 29 and have indicia thereon so that the height of the plungers may be ascertained by comparing the upper end of the threaded stems 26 with the indicia on the gauges.

25 Crank shafts 40 and 41 are journaled in suitable members 42 and an electric motor 44 is operatively connected with the crank shafts through gearing 45 which includes a main gear member *a* having gear segments *b* thereon to mesh with teeth *c* about the major portion of gear members *e* on the shafts 40 and 41 so as to cause intermittent rotation of these shafts in the same direction.

30 Feed lines 51 lead to the lower portions 35 of the compartment A, return lines 52 lead from the overflow and an outlet line 53 leads from the main spout 17.

From the above detailed description it will be understood that different ingredients are 40 forced up through the feed pipes 51 into the various compartments, the overflow or excess being taken care of by overflow 10 and return pipes 52. As the shafts 40 and 41 rotate the cranks 60 and 61 respectively thereof 45 actuate connecting rods 62 and 63 respectively thereof to reciprocate alternately gate valves 14 and 18 thereby regulating the flow of the ingredients into the main spout 17 in predetermined amounts, the quantity, obviously, 50 being regulated by the depth of the plungers 23 in the lower portions of the compartment.

This machine or apparatus will enable the rapid and correct measuring of the principal ingredients used in manufacture of paper. 55 It will also allow the proportion of the various ingredients to be changed quickly and without stopping the apparatus. Each proportion can be changed by raising or lowering the plunger in the respective measuring compartment which is a decided advantage 60 over the measuring chest now in common use such as is disclosed in the Beadle Patent No. 1,577,555 issued March 23, 1926, and is quite extensively used.

55 It is thought that the construction, opera-

tion, utility and advantages of this invention will now be quite apparent to those skilled in this art without departing from the spirit or scope of the invention as hereinafter claimed or sacrificing any of its advantages. 70

Having thus described my invention, what I claim as new is

1. An apparatus of the class described including a chest having a plurality of compartments with inclined bottoms to form upper portions and lower portions, feed lines leading to the upper portions, outlet openings in the lower portions, gates associated with the outlet opening, gates for separating the upper portion from the lower portions, and means for simultaneously and alternately operating the gates. 75

2. An apparatus of the class described including a chest having a plurality of compartments with inclined bottoms to form upper portions and lower portions, feed lines leading to the upper portions, outlets openings in the lower portions, gates associated with the outlet opening, gates for separating the upper portion from the lower portions, 85 means for simultaneously and alternately operating the gates; and means for controlling the capacity of the lower portions. 90

3. An apparatus of the class described including a chest having a plurality of compartments with inclined bottoms to form upper portions and lower portions, feed lines leading to the upper portions, outlet opening in the lower portions, gates associated with the outlet opening, gates for separating the upper portion from the lower portions, means for simultaneously and alternately operating the gates, and plungers slidably mounted in the lower portions to increase or decrease the capacity thereof. 100

4. An apparatus of the class described including a chest having a plurality of compartments with inclined bottoms to form upper portions and lower portions, feed lines leading to the upper portions, outlet openings in the lower portions, gates associated with the outlet opening, gates for separating the upper portion from the lower portions, means for simultaneously and alternately operating the gates, plungers slidably mounted in the lower portions to increase or decrease the capacity thereof, and means for controlling said plungers. 110

5. An apparatus of the class described including a chest having a plurality of compartments with inclined bottoms to form upper portions and lower portions, feed lines leading to the upper portions, outlet openings in the lower portions, gates associated with the outlet opening, gates for separating the upper portion from the lower portions, means for simultaneously and alternately operating the gates, plungers slidably mounted in the lower portions to increase or decrease the capacity thereof, means for con- 120

125

trolling said plungers, and vent pipes leading from the lower portions.

6. An apparatus of the class described including a chest having a plurality of compartments with inclined bottoms to form upper portions and lower portions, feed lines leading to the upper portions, outlet openings in the lower portions, gates associated with the outlet openings, gates for separating the upper portion from the lower portions, means for simultaneously and alternately operating the gates, plungers slidably mounted in the lower portions to increase or decrease the capacity thereof, means for controlling said plungers vent pipes leading from the lower portions, said means for operating the gate including crank shafts, means for intermittently operating the crank shaft, shanks, slideable through bearings formed in the chest, and connecting rods between the cranks of the crank shaft and the shanks.

7. An apparatus of the class described including a chest having a plurality of compartments with inclined bottoms to form upper portions and lower portions, feed lines leading to the upper portions, outlet openings in the lower portions, gates associated with the outlet opening, gates for separating the upper portion from the lower portions, means for simultaneously and alternately operating the gates, and means for taking care of the overflow from the upper portions.

8. An apparatus of the class described including a chest having a plurality of capacity adjustable compartments therein, inlet and outlet valves associated with the compartments and means for operating said valves.

9. An apparatus of the class described including a chest having a plurality of capacity adjustable compartments therein, supply and overflow conductors connected with the chest and in communication with said compartments, inlet and outlet valves associated with said compartment and means for operating said valves.

10. An apparatus of the class described including a chest having a plurality of capacity adjustable compartments therein, supply and overflow conductors connected with the chest and in communication with said compartments, inlet and outlet valves associated with said compartment and means for operating said valves, said means including gearing to alternately open one valve and close the other.

55 11. An apparatus of the class described including a chest having a plurality of compartments, said compartments having capacity adjustable chambers therein, supply and overflow conductors connected to the chest and communicating with said compartments, inlet and outlet valves associated with said chambers and means for operating said valves.

60 12. An apparatus of the class described including a chest having a plurality of com-

partments, said compartments having capacity adjustable chambers therein, supply and overflow conductors connected to the chest and communicating with said compartments, inlet and outlet valves associated with said chambers and means for operating said valves, said means including gearing for alternately closing one valve and opening the other.

In testimony whereof I affix my signature.

CHARLES V. PROCTOR.
